[57] CLAIM

The ornamental design for a bread slicing rack, as shown and described.

DESCRIPTION

FIG. 1 is a top, front, left side perspective view of a bread slicing rack showing our new design;

FIG. 2 is a bottom, rear, left side perspective view thereof with the side walls shown partially pivoted away from their vertical positions;

FIG. 3 is a top, front, left side perspective view thereof inverted and the side wall members shown folded to their storage position; and,

FIG. 4 is a top, rear, left side perspective view thereof in a different orientation.

The undisclosed right side view is identical to the left except for the flanges on both sides of the rear knife guides.
